U.S. Cl. D8—266

The drawing shows a perspective view of a strip of staples constructed in accordance with this invention. The broken line illustration of the printed matter is merely representative of the type of indicia that may appear on the staples. The side opposite that shown is identical to the side that is shown. The underneath of the top of the staples is a flat surface.

This application is a division of application Ser. No. 254,834, filed on May 18, 1972 and is directed solely to subject matter described and claimed in the original application as filed.

I claim:

The ornamental design for a strip of staples, as shown.
